UNITED STATES PATENT OFFICE.

PHILIP H. CHASE, OF EAST ORANGE, NEW JERSEY.

ELECTRIC SWITCH.

1,352,402.

Specification of Letters Patent. Patented Sept. 7, 1920.

Application filed March 1, 1916. Serial No. 81,415.

To all whom it may concern:

Be it known that I, PHILIP H. CHASE, a citizen of the United States, and residing at East Orange, in the county of Essex and 5 State of New Jersey, have invented a new and Improved Electric Switch, of which the following specification is a full disclosure.

This invention relates to electric switches, 10 and with regard to certain more specific features, to safety devices for use in connection with manually operated disconnecting switches for high-voltage circuits. The present invention is an improvement on the 15 invention set forth in my copending application for electric switch, Serial No. 80,923, filed February 28, 1916.

Among the objects of the present invention may be noted the provision of a practical and effective switch in which the operator cannot remove the operating hook from the switch blade at certain times during the cycle of operation of the switch; the provision of a simple and inexpensive safety 25 device to prevent improper manipulation of a switch in the hands of an inefficient or careless operator; the provision of improved apparatus of the above type of reliable action and durable under conditions of use; 30 and the provision of a switch in which the protective features are effective automatically and the danger of improper handling is reduced to a minimum. Other objects will be in part obvious and in part pointed 35 out hereinafter.

The invention accordingly comprises the features of construction, combinations of elements and arrangements of parts which are to be exemplified in the structure here- 40 inafter described, and the scope of the application of which will be indicated in the following claims.

In the accompanying drawings, in which are shown one or more of the various possible embodiments of this invention, 45

Figure 1 is a top plan view of a switch.

Fig. 2 is a side elevation of Fig. 1.

Fig. 3 is a top plan view of a modification of Fig. 1.

50 Fig. 4 is a side elevation of the switch of Fig. 3.

Fig. 5 is an end elevation of Fig. 3.

Fig. 6 is a detail of a spring and its associated parts.

Fig. 7 is a side elevation similar to Fig. 2, showing the invention applied to a single-pole double-throw switch.

Fig. 8 illustrates a preferred form of hook.

In considering the relation of this invention to the prior art, it may be noted that for some time past the users of manually operated switches, especially on high-voltage circuits, have encountered trouble through the failure of the operators to close the switches completely, or to open them far enough to break any arc that might form. These switches usually comprise simply a pair of spaced and relatively insulated contact blocks on which are mounted respectively a pivoted switch-blade and a pair of jaw-clips with which the blade contacts when the switch is closed. The blade may be in one or more parts, according to the size of the switch and the preference of the designer. In a double-throw switch, there is an additional contact-block, insulated relatively to the other two, and provided with a pair of jaw-clips to receive the switch blade when the switch is in the second of its two circuit-closing positions. There are a number of varieties of these switches, such as double and triple-pole switches, but it will suffice for the purpose of the present description, to confine the illustrations to a single-pole single-throw switch, it being understood that many if not all of the advantageous features of the present invention are applicable to double-throw, and multiple-pole, and other modifications of the prior-art switching devices.

Referring now more particularly to Figs. 1 and 2 of the drawings, there is illustrated at 1 a base or contact-block upon which are mounted the usual jaw-clips 2 adapted to receive the blade 3, which is pivotally supported upon another contact-block (not shown). The blade 3 is shown as made in one part, and there is therefore one pair of the jaw-clips 2 co-operating therewith when the blade is in its circuit-closing position illustrated more clearly in Fig. 2. When the switch is to be opened, the operator inserts in the aperture 7 in the blade 3 the nose 9 of a hook 10 preferably of the gen-

2

eral type illustrated in Fig. 8. The guard 18 prevents the operator from inserting the hook too far into the aperture 7. The nose 9 passes readily through the large part 11 of the aperture 7, but is too large to pass through the smaller parts 12, 13 of said aperture. The operator, in order to pull the blade 3 away from the jaw-clips 2 to open the switch, pulls in an upward direction on the hook 10; this causes the hook to enter the upper reduced portion 12 of the aperture 7. In the last position the catch 28 of the latch portion 25 of the pivoted member 16 hooks over the upper edge 31 of the guide member 17 fixed to the blade 3, and the blade 3 is thus held closed against accidental displacement. The coiled spring 32 tends to press the latch or lock 25 clockwise. In opening the switch, the operator pulls upward on the hook. This causes the shank 14 of the hook to enter the upper reduced portion 12 of the aperture 7, and in doing so, the shield portion 15 of the pivoted member 16 is forced toward the left, thereby swinging the member 16, and consequently the latch 25, counter-clockwise against the action of the spring 32, and as a result the catch 28 shifts toward the left to a position beyond the outer end of the edge or surface 31. This unlocks the switch and permits the operator to pull the switch blade upward (clockwise) until the switch is entirely open. When the switch is far enough open so that the lower end of the guide 17 is above the catch 28, the coil spring 32 causes the lock 25 to return clockwise to its position of rest, with the portion 26 thereof against the stop surface 35 of the fixed base 19 on which the member 16 is pivotally mounted. The operator can then readily remove the hook 10 from the aperture 7. If, however, the operator attempts to remove the hook from the switch blade while the catch 28 on the lock 25 engages the guide 17 on the blade 3, he will be unable to do so, because the left or blanketing edge 30 of the latch 25 is at this time to the left of its position illustrated in Fig. 2, and partially shields or blankets the wide part 11 of the aperture 7 to such an extent that no part of the aperture is large enough to permit the nose 9 of the hook 10 to pass through it. The operator is thus unable to remove the hook from the switch blade throughout a predetermined range or portion of the movement of the blade, the magnitude of said range depending on the vertical length of the blanketing edge 30, and the length of the guide 17. This range of movement of the blade through which the protective device of the present invention is effective, may be varied to any desired extent; the protective device may be made effective from the circuit-closing position of the blade (illustrated in Fig. 2) to a posi-

tion considerably beyond the position where contact is actually broken, in order to make sure that any arcing at the contacts is broken prior to disconnection of the handle from the blade; or the protected range may extend only to the point where contact is actually broken; or the blanketing edge 30 and the guide 17 may be made shorter, with a corresponding reduction of cost, and the protected range of movement will then extend from the closed position of the switch throughout only part of the angle through which the blade is in contact with the jaw-clips 2. In closing the switch, a similar protection is afforded, in that the operator cannot remove the hook until the switch is substantially or entirely closed and is locked in this closed position: as the switch blade 3 approaches the jaw-clips 2 in closing, the beveled surface 38 of the catch 28 causes the catch to ride outwardly on the guide 17 of the blade 3, thereby swinging the lock 25 counter-clockwise against the action of the spring 32; during the ensuing downward movement of the blade 3, the catch rides along the guide 17, causing the blanketing part 30 of the latch 25 to reduce the size of the aperture 7 sufficiently to prevent removal of the hook; when the switch reaches its circuit-closing position, illustrated in Fig. 2, the spring 32 swings the catch 28 clockwise until said catch passes over the upper edge 31 of the guide 17, thereby locking the switch in its closed position and restoring the parts to the relative positions indicated in Fig. 2. Since the surface 30 now no longer blankets the aperture 7, the hook may be readily removed therefrom. The proportioning of parts, particularly the shape of the aperture 7, is illustrated somewhat conventionally, since the invention is not limited to any particular shape of said aperture, nor indeed to any specific arrangement or disposition of parts not inconsistent with the present disclosure. The construction is illustrated in connection with a blade constructed of a single piece, but would be equally applicable to a blade constructed of two or more parts; and it may be generally stated, at this point, that many if not all of the several embodiments of the invention herein illustrated may be utilized with each of the various types of switches known in the art.

In Figs. 1 and 2, the pivoted member 16 enters a vertical slot in the apertured extension 21 on the blade 3.

In the modification illustrated in Figs. 3, 4 and 5, this relative arrangement is reversed by having the apertured extension 21 on the blade enter a vertical slot in the pivoted member 16, and the lock or latch 25 carrying the catch 28 takes the form of a pair of upstanding ears, best shown in Fig. 3. A preferred type of spring 32 for

pressing the pivoted member clockwise about its bearing pin 27 is illustrated in Fig. 6.

The application of the invention to a double-throw switch is shown in Fig. 7; the 5 pivoted member 16 is duplicated to provide a protected range of movement of the blade 3 at both ends of its double throw or stroke.

The pivoted member 16 may be attached at the near or hinge side of the jaw-clips 2, 10 instead of at the far side, as shown in Figs. 1 to 7, in which case the guide member 17 would preferably be offset with respect to the longitudinal axis of the blade. This arrangement would effect a saving in size of the 15 several parts, for a given protected angular travel of the blade 3, because the parts would be located nearer the hinge of the blade.

The guide 17, pivoted member 16, pedestal 19 therefor, and the bearing pin 27 for said 20 pivoted member may be made of any suitable material consistent with mechanical strength and cheapness. In fact, the guide 17 may be simply a surface formed on the 25 blade 3 itself, instead of being on a part secured to the blade, as in the drawings here-with.

The hook 10 illustrated in Fig. 8 comprises preferably a wooden or other insulating pole or handle 40, upon which is fitted 30 a ferrule 41, of bronze or other suitable material. This ferrule extends longitudinally of the handle 40 for a short distance, and then transversely, and the transverse or lateral shank 14 of the ferrule terminates in 35 a nose 9 somewhat larger than the shank but smaller than the aperture 7 of the switch with which the hook is to be used; the shank is preferably provided with a guard 18 larger than the aperture 7, so that the hook 40 cannot be inserted too far in said aperture.

From the above it will be seen that the several objects of the invention are achieved, and other advantageous results attained.

As various changes might be made in the 45 above construction, and as the above invention might be embodied in different forms, it is intended that all matter set forth in the above description and in the accompanying drawings, shall be interpreted as illustrative and not in a limiting sense.

Having thus revealed my invention, I desire to claim as new and secure by Letters Patent in the United States:

1. An electric switch combining a blade 55 apertured to receive a hook provided with a nose, a contact-block, contact clips mounted thereon to coöperate with said blade, and a lock comprising a latch mounted on the contact-block, said latch comprising means 60 for preventing removal of the hook during a predetermined range of the movement of the blade.

2. An electric switch combining a blade 65 apertured to receive a hook provided with a nose, a contact-block, contact clips mounted

thereon to coöperate with said blade, and a shield mounted to rotate about a fixed pivot and adapted to blanket said aperture throughout a portion of the movement of the blade to an extent sufficient to prevent 70 removal of the hook from said aperture throughout said portion.

3. An electric switch combining a blade member having an aperture to receive a hook provided with a nose, a contact-block, 75 clips mounted thereon to coöperate with said blade, and means comprising a shield mounted to rotate about a fixed pivot for preventing removal of the hook from the blade throughout a portion of the movement of 80 the blade greater than the range of movement of the blade during which the blade contacts with said clips.

4. An electric switch combining a blade member, having an aperture to receive a 85 hook provided with a shank and a nose, fixed contact clips coöoperating with said blade, and a latch mounted on a fixed portion of the switch for locking said switch in circuit-closing position, said latch being adapted 90 to blanket said aperture throughout a portion of the movement of said blade to reduce said aperture to a size larger than said shank but smaller than said nose and thus prevent removal of said hook from said aperture throughout said portion of the movement of the blade. 95

5. An electric switch combining a blade member comprising two spaced parts having registering apertures to receive a hook 100 provided with a shank and a nose, fixed contact means coöoperating with said blade, and a shield pivotally mounted on a fixed portion of the switch and extending between said parts and blanketing said apertures 105 throughout a portion of the movement of said blade to reduce said apertures to a size larger than said shank but smaller than said nose and thus prevent removal of the hook from said apertures throughout said portion of the movement of the blade. 110

6. An electric switch combining a blade having an aperture to receive a hook provided with a shank and a nose, fixed contact means coöoperating with said blade, and 115 a latch mounted on a fixed portion of the switch to lock said blade in its circuit-closing position and provided with members extending adjacent said blade for blanketing said aperture throughout a portion of the movement of 120 said blade to reduce said aperture to a size larger than said shank but smaller than said nose and thus prevent removal of said hook from said aperture throughout said portion of the movement of 125 the blade.

7. An electric switch combining a blade, an extension on said blade having an aperture to receive a hook provided with a shank and a nose, and having a slot, fixed contact 130

means coöperating with said blade, and a latch device mounted on a fixed pivot and acting at a point adjacent said fixed contact means to lock the switch in circuit-closing position and extending through said slot throughout a portion of the movement of the blade and blanketing said aperture throughout a portion of the movement of the blade to an extent sufficient to prevent removal of said hook from said aperture throughout said latter portion of the movement of the blade.

8. An electric switch combining a blade member apertured to receive a hook provided with a nose, a contact-block, contact clips mounted thereon to coöperate with said blade, a latch mounted on the contact-block and locking said blade in its circuit-closing position, means operated by said hook for releasing said latch, and means for preventing removal of the hook from said aperture during a predetermined range of the movement of the blade.

9. An electric switch combining a blade apertured to receive a hook provided with a nose, a contact-block, contact means mounted thereon to coöperate with said blade, a latch pivotally mounted on a fixed portion of the switch for locking said blade in its circuit-closing position, and a member blanketing said aperture throughout a portion of the movement of the blade to an extent sufficient to prevent removal of the hook from said aperture throughout said portion.

10. An electric switch combining a double-throw blade member having an aperture to receive a hook provided with a shank and a nose, fixed contact means coöperating with said blade at the end of the throw of said blade, means associated with said contact means and mounted on a fixed portion of the switch for locking said blade in its circuit-closing position, means operated by the hook for releasing the locking means and simultaneously blanketing said aperture to an extent sufficient to prevent the removal of the hook from said aperture, and means for retaining said locking means in said blanketing position throughout a predetermined portion of the range of movement of the blade to prevent removal of the hook from said aperture throughout said portion.

11. An electric switch combining a blade member having an aperture to receive a hook provided with a shank and a nose, fixed contact means coöperating with said blade, a guide mounted on the blade at a point adjacent said contact means, means mounted on a fixed pivot and adapted to lock said blade in its circuit-closing position, and means operated by said hook for releasing said locking means and simultaneously blanketing said aperture to reduce said aperture to a size larger than said shank but smaller than said nose and thus prevent re-

moval of said hook from said aperture, said guide maintaining said locking means in said blanketing position throughout a predetermined range of the movement of the blade.

12. An electric switch combining a blade, an extension on said blade having an aperture to receive a hook provided with a shank and a nose, and having a slot, fixed contact means coöperating with said blade, a member mounted on a fixed pivot and extending through said slot throughout a portion of the movement of the blade and locking said blade in its circuit-closing position, and means operated by said hook for moving said member to release said lock and simultaneously blanket said aperture to reduce said aperture to a size larger than said shank but smaller than said nose and thus prevent removal of said hook from said aperture, said member maintaining said blanketing position throughout a predetermined range of the movement of the blade.

13. An electric switch combining a blade having an aperture to receive a hook provided with a shank and a nose, fixed contact means coöperating with said blade to close a circuit, a member fixed on said blade, a latch pivotally mounted on said contact means and having a catch coöperating with said member to lock the blade in its circuit-closing position, means tending to maintain said latch in its locking position, and an extension on said latch partially blanketing said aperture whereby when said hook is inserted in said aperture the initial movement of the hook in the direction for opening the switch forces said catch away from said member to unlock said blade.

14. An electric switch combining a pivoted blade having an aperture to receive a hook provided with a shank and a nose, a fixed contact-block, contact clips mounted thereon to coöperate with said blade to close a circuit, a guide mounted on said blade, a latch pivotally mounted on said contact-block and having a catch coöperating with said guide to lock the blade in its circuit-closing position, a spring tending to maintain said latch in its locking position, an extension on said latch partially blanketing said aperture whereby when said hook is inserted in said aperture the initial movement of the hook in the direction for opening the switch forces said catch away from said guide to unlock said blade and simultaneously blanketing said aperture to an extent sufficient to prevent removal of the hook from said aperture, said guide coöperating with said latch to maintain said latch in said blanketing position throughout a predetermined portion of the movement of the blade to prevent removal of the hook from said aperture until the blade has been moved through a predetermined angle in its circuit-
